UNITED STATES PATENT OFFICE.

FRANK L. SHALLENBERGER, OF BRADDOCK, ASSIGNOR TO CARNEGIE,
PHIPPS & CO., (LIMITED,) OF PITTSBURG, PENNSYLVANIA.

HEATER FOR COAL-SCREENS.

SPECIFICATION forming part of Letters Patent No. 362,793, dated May 10, 1887.

Application filed November 11, 1886. Serial No. 218,597. (No model.)

To all whom it may concern:

Be it known that I, FRANK L. SHALLENBERGER, a resident of Braddock, in the county of Allegheny and State of Pennsylvania, have 5 invented certain new and useful Improvements in Heaters for Coal-Screens; and I do hereby declare that the following is a full, clear, and exact description of the invention, which will enable others skilled in the art to which it appertains to 10 make and use the same, reference being had to the accompanying drawings, which form a part of this specification, and in which—

Figure 1 is a side elevation in outline of a coal-tipple complete, showing its different 15 parts and indicating the position of the cars into which the coal and dust are discharged after screening. Fig. 2 is a perspective view of one of the screens with its hopper and heating device, one side being broken away in part 20 to show the interior arrangement of the heating device. Fig. 3 is a longitudinal vertical section of the screen with its hopper and heating device, and Fig. 4 is a vertical transverse section of the same.

Like letters of reference denote corresponding 25 parts in the several figures.

My invention relates to a certain improvement in coal-screens, having for its object to provide means whereby the screen, as well as 30 the hopper forming part thereof, may be heated in cold weather. Operators of coal-mines, as is well known, experience considerable difficulty in screening coal in cold and wet weather, from the fact that the wet coal and slack will 35 freeze to the screen-bars and to the sides and bottom of the slack or dust hopper, thereby choking up and obstructing the same, so as to seriously interfere with the operation of screening, besides causing delay and loss of 40 time and labor in removing the coal and slack which adheres to the screen and screen-hopper.

It is the object of my invention to avoid 45 this difficulty by providing the coal-screens and their hoppers with a heating attachment or device for keeping them dry and warm; and to this end I have devised the heating attachment or apparatus which will be herein-after more fully described and claimed.

In the accompanying drawings, A denotes 50 the coal screen or screens, and B the dust or

slack hopper secured thereto. The bottom J of this hopper is, as usual, pitched at a greater angle than the screen proper, so as to readily carry off the waste product to and through the 55 dust-chute E' to a car or suitable receptacle placed below.

The letter H on Fig. 1 denotes the weigh-pan, and E is the conveyer chute or chutes by which the screened and sorted coal is conveyed 60 to the cars or bins.

The hopper B is provided with a false bottom, consisting of a series of plates, C C C, extending transversely across the bottom J of the hopper, from side to side, and forming a series 65 of steps overlapping one another, as shown. These steps or plates C are fastened to the sides of the hopper, either permanently or removably, in any suitable manner, and may be supported at their overlapping ends by short 70 posts or supports F. An aperture is made in the true bottom of the hopper for the insertion of a pipe or flue, D, connecting the hopper with any suitable heat-generator.

From the foregoing it will be seen that the 75 heat from the generator will enter the space formed between the true and false bottom of the hopper, from which it will be diffused over the entire length and width of the hopper, underneath the overlapping steps or plates 80 which form the false bottom, thus keeping said false bottom dry and warm and preventing coal dust and slack from sticking to it. The heat then escapes through the openings or spaces between the successive steps formed by 85 said plates and ascends up into the body of the screen, between the screen-bars, keeping them, as well as the sides of the screen box or frame, dry and warm also, and thereby preventing the wet coal from freezing to the bars or frame, 90 so that the work of screening may continue without interruption even in the coldest weather.

Having thus described my invention, I claim and desire to secure by Letters Patent of the 95 United States—

1. The combination, with a coal-screen, of a hopper secured thereto, the bottom of which is provided with an aperture, a false bottom within said hopper forming a heating space or chamber, said false bottom being provided 100 with openings for the escape of the heat up

into the hopper and between the screen-bars, and a heat-inlet pipe, substantially as and for the purpose set forth.

2. The combination, with a coal-screen, of a hopper secured thereto, the bottom of which is perforated, a chute, a series of overlapping plates, posts at the overlapping ends of said plates, said plates and posts forming a false bottom within said hopper, and a heat inlet

pipe, substantially as and for the purpose set forth.

In testimony that I claim the foregoing as my own I have hereunto affixed my signature in presence of two witnesses.

FRANK L. SHALLENBERGER.
